UNITED STATES PATENT OFFICE.

HENRY C. PILANT, OF OAK GROVE, MISSOURI.

COIN-RECEPTACLE FOR MAIL-BOXES.

1,136,974.

Specification of Letters Patent. Patented Apr. 27, 1915.

Application filed December 30, 1913. Serial No. 809,519.

To all whom it may concern:

Be it known that I, HENRY C. PILANT, citizen of the United States, residing at Oak Grove, in the county of Jackson and State 5 of Missouri, have invented certain new and useful Improvements in Coin-Receptacles for Mail-Boxes, of which the following is a specification.

This invention relates to coin receptacles. 10 The primary object of the invention is to provide a device for the purpose set forth, which may be supported within a mail box or other common form of rural free delivery box, the receptacle being adapted to contain 15 coin intended for the postman, and being capable of easy operation to discharge the coin therefrom.

A further object of the invention is to provide a coin receptacle which, when in normal position, will effectually hold the coin therein, and which may be tilted to discharge the coin therefrom.

A further object of the invention is to provide a coin receptacle adapted for attachment within mail boxes as now manufactured, the device being particularly adapted for use in connection with the type of mail box used in rural free delivery service, without structural change to such boxes. And a 30 still further object of this invention is to generally improve the construction and increase the efficiency of devices of the above described character.

For a full understanding of the invention 35 reference is to be had to the following description and accompanying drawings, wherein:

Figure 1 is a perspective view showing my improved coin receptacle attached to the end 40 wall of a mail box, the box being broken away. Fig. 2 is a front elevation showing the coin receptacle in operative relation to the mail box, the box being shown in section. Fig. 3 is a plan view of the blank 45 from which the coin receptacle is formed. Fig. 4 is a detail perspective view of one of the supporting cleats secured to the side walls of the receptacle.

Corresponding and like parts are referred 50 to in the following description and indicated in all the views of the accompanying drawings by the same reference characters.

My improved coin receptacle includes a body portion 10 having integrally formed 55 thereon an outwardly flared upper extremity

11, constituting a mouth, the forward edges of the body portion being outwardly curved, as shown. Preferably, the receptacle is formed from a blank of suitable sheet metal and includes side walls 12, intermediate of 60 which is defined a bottom wall 13, which extends at one extremity to form a portion of the back wall 14.

From the side edges of the bottom wall 13, the front edges of the side wall 12 are cut 65 away, throughout the greater portion of their length, along inwardly extending curved lines to form reduced extremities 15 and 16 at the outer ends of said walls. The reduced extremity 15 is continued at its forward edge to form a relatively wide angularly disposed flap 17, a similarly disposed flap 18 being formed on the reduced extremity 16. The combined width of said flaps 17 and 18 is slightly greater than the 70 width of the bottom wall 13. The rear edges of the side walls 12, coextensive with the reduced extremities 15 and 16, are undercut, and one of said walls is formed with a continuous rearwardly disposed flap 19. 75 The rear edge of the opposite wall is formed with a similar flap 20 for a portion of its length, the reduced extremity 16 adjacent said flap being continued to form a relatively wide angularly disposed flap 21, having 80 formed on its inner edge a reduced extremity 22. In folding the blank thus formed, the side walls 12 are bent along straight lines continuing from the side edges of the end flap 14 to assume a position at right angles 85 to the bottom wall 13. The reduced extremities 15 and 16 of said side walls 12 are then flared outwardly, the side walls being connected adjacent their upper extremities by the overlapping ends of the flaps 17 and 18, which are bent inwardly at right angles 90 to the reduced extremities 15 and 16. The flaps 19 and 20 are then bent to lie against the outer face of the end flap 14, the flap 21 being bent inwardly to form a continuation 95 of said end flap, to which it is secured by the reduced extremity 22, it being understood, of course, that the upper extremity of the flap 19 will lie against the outer face of the flap 21. Thus folded, the overlapping edges 100 of the blank may be secured in any suitable manner, as by riveting. Secured to the sides of the body portion 10 of the receptacle and forwardly of the center thereof longitudinally, are vertically disposed cleats 23. The 110

said cleats are preferably riveted in position and have formed thereon, adjacent their upper extremities outstanding pindle lugs 24.

Pivots supporting the receptacle is a 5 U-shaped bracket 25, the arms 26 of which embrace the lower portion of the body portion 10 of the receptacle and are longitudinally bowed adjacent their upper extremities to extend adjacent the side walls 11 and 10 parallel thereto, said arms being provided with apertures adjacent their upper extremities adapted to receive the pindle lugs 24. Riveted or otherwise secured to the outer face of the forward end portion 27 is a tilting lever 28 which extends above the discharge opening 29 of the receptacle and terminates in a downwardly deflected extremity 30. The receptacle is normally supported in counterbalanced position upon the 15 bracket 25, causing the discharge opening 29 to be held upwardly, the receptacle being limited in its tilting movement by the transversely extending portion 32 of the bracket 25 which engages against the bottom wall 20 of the receptacle.

As illustrated, my improved coin receptacle is designed to be secured to the inner face of one wall of a mail box, conventionally shown at 33, the box forming a housing 30 for the device. Suitable apertures may be provided in one of the bracket arms 26, said apertures being designed to receive bolts 34 which extend through the adjacent side wall of the box.

35 In the practical use of my invention, the coin is placed within the receptacle, where it will be held pending removal, the coin collecting in the rear portion thereof. To effect the discharge of the coin from the receptacle the thumb may be placed upon the extremity of the tilting lever 28, the remaining fingers of the hand being held under the adjacent discharge opening 29, when a downward pressure upon the tilting lever 40 will effect the ejection of the coin. It may be noted at this point that in forming my improved coin receptacle as above described, the body portion 10 thereof provides a coin receiving pocket, the upper extremities 11 45 of the walls forming a coin receiving chute, a coin discharge chute being formed by the wings at the forward extremity of the coin receiving pocket. It may be further noted that the bracket 25 being resilient, the arms 50 55 thereof may be sprung outward to disengage the lugs 24 carried by the coin receptacle when the receptacle may be removed from the bracket, this construction being found convenient when attaching the device 60 to a mail box. Furthermore, said resilient arms will firmly engage the lugs 24, in the operative supported position of the coin receptacle and thereby prevent its accidental displacement. It will, therefore, be seen 65 that I provide a very simple and convenient

device, for the purpose set forth which may be easily attached to a great variety of mail boxes, as now in general use, and which may be easily operated to effect the ejection of the coin placed therein, thereby overcoming the difficulty at present experienced in the depositing and collection of coins under similar circumstances.

Having thus described the invention, what is claimed as new is:

1. A blank of the character described, including a body portion bent at right angles along parallel lines to form bottom and side walls, the side walls being extended at their upper ends to form reduced extremities 70 adapted to provide a flared mouth portion, the forward edges of said reduced portions being continued to form flaps adapted to be folded at right angles, the extremities of said flaps overlapping to form a forward end portion, the body portion of the blank being formed with a rearwardly extending end flap adapted to be folded at right angles to the bottom wall, one of said reduced extremities being undercut along its rear edge, 80 and such reduced extremity and adjacent side wall having a continuous flap formed thereon, adapted to be bent at right angles, the rear edge of the opposite reduced extremity being formed with a relatively wide 85 flap adapted to be bent at right angles to form a portion of the rear end wall, such relatively wide flap having a reduced extremity thereon adapted to bear against the end flap formed adjacent the bottom wall, 90 one of said reduced extremities being undercut along its rear edge, and such reduced extremity and adjacent side wall having a continuous flap formed thereon, adapted to be bent at right angles, the rear edge of the opposite reduced extremity being formed with a relatively wide 95 flap adapted to be bent at right angles to form a portion of the rear end wall, such relatively wide flap having a reduced extremity thereon adapted to bear against the end flap formed adjacent the bottom wall, 100 and such reduced extremity and adjacent side wall having a continuous flap formed thereon, adapted to be bent at right angles, the rear edge of the opposite reduced extremity being formed with a relatively wide flap adapted to be bent at right angles to form a portion of the rear end wall, such relatively wide flap having a reduced extremity thereon adapted to bear against the end flap formed adjacent the bottom wall, 105 and such reduced extremity and adjacent side wall having a continuous flap formed thereon, adapted to be bent at right angles, the rear edge of the opposite reduced extremity being formed with a relatively wide flap adapted to be bent at right angles to form a portion of the rear end wall, such relatively wide flap having a reduced extremity thereon adapted to bear against the end flap formed adjacent the bottom wall.

2. A device of the character described including a support, a coin receptacle mounted for pivotal movement thereon, said receptacle being formed with a coin receiving pocket, a coin receiving chute opening 110 into said pocket, said chute having converging walls and a coin discharging chute arranged at right angles to the coin receiving chute, and means for tilting the receptacle.

3. A device of the character described including an integral support having spaced arms joined by a connecting portion, a coin receptacle mounted for pivotal movement upon the support between said arms, said receptacle having a mouth and a discharge opening and being normally counterbalanced upon the support, the connecting portion of the support being arranged to limit the oscillatory movement of the receptacle, and means for tilting said receptacle.

4. A device of the character described including a support having spaced resilient arms having apertures formed therein adjacent their outer extremities, a coin recep-

- tacle mounted for pivotal movement upon the support, said receptacle having a mouth and a discharge opening, cleats secured to the side walls of the receptacle, pintle lugs 5 formed on said cleats and adapted to engage within the apertures formed in said arms, the upper extremities of said arms being adapted to be sprung apart to receive said pintle lugs.
- 10 5. A blank of the character described adapted when folded to form a coin receptacle having a coin receiving chute, the walls of said coin receiving chute being flared outwardly and upwardly spaced from

the bottom wall of the receptacle, and a 15 coin discharge chute extending at right angles to said coin receiving chute, the walls of said discharge chute being cut away upon their free edges from the inner extremity 20 of the coin receiving chute to the outer extremity of the coin discharge chute.

In testimony whereof I affix my signature in presence of two witnesses.
